Primary Examiner—Dominic Simone**Attorney, Agent, or Firm**—Fish & Richardson P.C.**[57] CLAIM**

The ornamental design for a shoe eyelets, as shown and described.

DESCRIPTION

FIG. 1 is a top view of shoe eyelets showing my new design; FIG. 2 is a right side view thereof; FIG. 3 is a front view thereof; and, FIG. 4 is a left perspective view thereof. The dotted line showing of a shoe upper and shoe sole is for illustrative purposes only and forms no part of the claimed design.
